CLAIM

The ornamental design for a television receiver, as shown and described.

DESCRIPTION

FIG. 1 is a front perspective view of the television receiver showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a back perspective view thereof;

FIG. 9 is a front perspective view showing a state of use with the front display raised, in an alternate position; and,

FIG. 10 is a front perspective view showing a state of use with the front display raised and rotated 90 degrees, in an alternate position.

The broken lines depict portions of the television receiver that form no part of the claimed design.

1 Claim, 10 Drawing Sheets
